US0D1043553S

(12) **United States Design Patent** (10) **Patent No.:** **US D1,043,553 S**
(45) **Date of Patent:** **** Sep. 24, 2024**

(54) **BATTERY**

(71) Applicant: **TIM AKILLI KIYAFETLERİ VE BİLİŞİM TEKNOLOJİSİ ANONİM SİRKETİ**, İstanbul (TR)

(72) Inventors: **Enes Kar**, İstanbul (TR); **Arda Uslu**, İstanbul (TR)

(73) Assignee: **TIM AKILLI KIYAFETLERİ VE BİLİŞİM TEKNOLOJİSİ ANONİM SİRKETİ**, İstanbul (TR)

(**) Term: **15 Years**

(21) Appl. No.: **35/516,609**

(22) Filed: **Dec. 2, 2022**

(80) **Hague Agreement Data**

Int. Filing Date: **Dec. 2, 2022**

Int. Reg. No.: **DM/227377**

Int. Reg. Date: **Dec. 2, 2022**

Int. Reg. Pub. Date: **Mar. 17, 2023**

(51) **LOC (14) Cl.** 13-02

(52) **U.S. Cl.**

USPC **D13/103**

(58) **Field of Classification Search**

USPC D13/102-106, 110, 118, 119, 184, 199; D14/253, 432, 434

CPC H01M 6/00; H01M 6/14; H01M 6/10; H01M 10/52

See application file for complete search history.
